FURNACE

John F. O. Stratton, Pelham Manor, N. Y.

Application September 27, 1928, Serial No. 308,712

4 Claims. (Cl. 110—28)

The present invention relates to improvements in furnaces, and is particularly applicable to furnaces of the vertical jet combustion type, such for example as is shown in my Letters Patent No. 1,640,158.

In vertical jet combustion furnaces, the fuel is held in suspension by an upward blast of air, and the amount of air supplied in the blast is varied in accordance with the amount of fuel to be consumed. The non-combustible matter, being heavier than the fuel, falls against the force of the air blast into an ash pit. In furnaces, where the fuel is burned while in a suspended state, a small amount of finely divided solids may be entrained in the outgoing products of combustion. These solids are in the nature of fine cinders, and may contain a small percentage of unconsumed carbon which is usually graphitic in character. The entrained solids are baffled out of the gases of combustion, and are collected in a suitable cinder chamber separate from the ash pit. The combustible in the cinders passing over with the gases burns only at a relatively high temperature.

The primary object of the present invention resides in the provision of novel means for automatically returning the solids collecting in the cinder chamber to the combustion chamber. By reason of this construction, the necessity of periodically and manually removing the collecting cinders, which involves extra labor and inconvenience, is avoided. By immediately removing the cinders, danger of fire in the cinder chamber is reduced. Also, the combustible in the cinders is not lost as would otherwise be the case, but is burned, thereby increasing the efficiency of combustion.

Another object of the invention resides in returning the cinders to the hottest part of the combustion chamber so that the combustible will be consumed.

The amount of cinders passing over with the gases of combustion obviously will vary with the air pressure which in turn is varied with the amount of fuel supplied. A further object therefore resides in the provision of a novel means of the foregoing character which will vary in capacity with the supply of air and fuel, and hence with the amount of cinders to be handled.

A more specific object resides in the provision of a novel suction device for removing the cinders, the device being operable by air from the air supply for the blast.

Further objects and advantages will become apparent as the description proceeds.

55 In the accompanying drawing, the figure is a

vertical sectional view of a furnace embodying the features of my invention.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the exemplary embodiment of the invention in the drawing, the invention is applied to a vertical jet combustion furnace of a particular construction, but it is to be understood that the invention is applicable to furnaces of a variety of constructions.

In the preferred form, the furnace comprises a combustion chamber 10 of suitable form comprising a rear wall 11, a front wall 12, and inclined rear and front bottom walls 13 and 14. These walls may be made of any suitable material, such as refractory material. The walls 13 and 14 at their lower edges define a narrow opening 15 defining the upper rear and front edges of a throat preferably formed by a peripheral air chamber 16, and serve to direct the coal and slag falling thereon toward the throat. Fuel, such as finely divided coal, may be fed into the chamber 10 through a spout 17 in the front wall 12.

Underlying the combustion chamber 10 is a closed ash pit 18 which also serves as an air pressure chamber. Ashes may be removed from the pit 18 through an opening 19 normally closed by a door 20.

The air chamber 16 opens downwardly to the ash pit 18, and is connected through a duct 21 to an air pressure chamber 22 adapted to be supplied with air under pressure from a suitable source, such as a blower (not shown). A valve or damper 23 serves as a means for controlling the supply of air to the chamber 18.

Suitably mounted in the ash pit 18, directly under the throat 16 is a grate mechanism 24. In the present instance, the grate mechanism 24 defines a narrow adjustable space 25 extending longitudinally of the throat 16 and serving as a nozzle for directing a blast of air from the ash pit 18 into the combustion chamber 10. The grate mechanism 24 is movable transversely of the throat 16 so as to shift the region of the air blast.

Mounted in the upper part of the combustion

chamber 10 are suitable heat absorbing tubes 26 and drums 27, and a series of baffles 28, 29 and 30 for directing the products of combustion in a tortuous path among the tubes. The products 5 of combustion may leave the chamber 10 through a suitable exhaust stack 31.

Underlying the baffles 28, 29 and 30 is a cinder collecting chamber 32 which is separated from the chamber 10 by the wall 11, and which has a 10 rear wall 33 also constituting the rear outer wall of the furnace structure. The baffles 28 and 29 serve to separate out any entrained solids in the gases of combustion, and the lower ends thereof are inclined rearwardly so as to direct 15 these solids into the cinder chamber 32. The bottom of the cinder chamber 32 is closed by a suitable sliding gate 34 for giving access to the interior.

The cinders collecting in the chamber 32 are 20 flocculent, and frequently contain a small percentage of combustible. Usually this combustible is in the form of graphitic carbon which burns only at relatively high temperatures. Means is provided for returning the cinders from the 25 chamber 32 to the chamber 10. In the present instance, this means comprises an induction tube 35 which extends through the walls 11 and 13. Preferably, the induction tube 35 opens to the 30 lower part of the combustion chamber 10, which is in the hottest zone, so that any combustible in the cinders will be consumed. The non-combustible matter in the cinders then will pass with the ashes to the ash pit 18. Extending centrally a short distance into the inlet end of 35 the induction tube 35 is an air injection pipe 36 which is connected to a suitable source of pressure fluid, such as the air chamber 22. A suitable valve 37 for regulating the supply of injection air is interposed in the pipe 36 outside 40 of the furnace. It will be evident that the supply of injection air will vary with the supply of air to the ash pit 18, and hence with the amount of cinders to be handled. By reason of this construction, the cinders will be removed from 45 the chamber 32 as fast as they collect, and will be sprayed into the hottest zone in the combustion chamber 10 where the combustible matter will be consumed and from where the non-combustible matter will pass to the ash pit.

50 It will be evident that I have provided a novel and highly advantageous furnace which is relatively simple and inexpensive in construction. By returning the cinders to the combustion chamber, the combustible therein which would otherwise be wasted is consumed, and at the same time the cinders are not permitted to accumulate in the cinder chamber. This prevents the possibility of the combustible in the cinders igniting in the chamber 32, and also obviates the necessity of manually cleaning the chamber at frequent intervals.

I claim as my invention:

1. A furnace comprising, in combination, a 65 combustion chamber having a restricted throat at its lower end, means for creating an upwardly directed blast of air through said throat, said means including an air supply duct with

a control valve, a source of air pressure for said means, means for introducing comminuted fuel into the upwardly directed blast, baffles for deflecting the gases of combustion to baffle out entrained solids, a chamber for receiving said baffled solids, an induction tube connecting said chambers, and an air injection pipe opening into the inlet end of said tube in said last mentioned chamber, said pipe being connected to said duct at the discharge side of said valve. 80

2. A furnace comprising, in combination, a combustion chamber having a restricted throat at its lower end, means for creating an upwardly directed blast of air through said throat, a source of air pressure for said means, means for introducing comminuted fuel into the upwardly directed blast, baffles for deflecting the gases of combustion to baffle out entrained solids, a chamber for receiving said baffled solids, an induction tube connecting said chambers, and an air injection pipe opening into the inlet end of said tube in said last mentioned chamber, said pipe being connected to said source. 85

3. A furnace comprising, in combination, an upright combustion chamber having a rear fire wall, means for directing a blast of air upwardly into said chamber, an adjustable source of air under pressure for said means, means for introducing comminuted fuel into the blast, a cinder chamber disposed at the rear of said wall and out of the path of the gases of combustion, heat absorbing elements mounted in the upper end of said combustion chamber and over said wall and said cinder chamber, a plurality of baffle walls disposed among said elements, certain of said baffle walls being disposed to direct the gases of combustion for a portion of their travel among said elements downwardly at a point over said cinder chamber to baffle out entrained solids in the gases and to direct the solids into said cinder chamber, an induction passage opening from the lower end of said cinder chamber to the lower end of said combustion chamber to discharge the solids into the lower portion of the blast, and an air injection line opening into the inlet end of said passage, said line being connected to 100 said air source. 105

4. A furnace comprising, in combination, an upright combustion chamber, means for directing a blast of air upwardly into said chamber, a source of air under pressure for said means, means for introducing comminuted fuel into the blast, a cinder chamber disposed out of the path of the gases of combustion, heat absorbing elements mounted in the upper end of said combustion chamber and over said cinder chamber, a plurality of baffle walls disposed among said elements to baffle out entrained solids in the gases, certain of said baffle walls being disposed to direct said solids into said cinder chamber, an induction passage opening from the lower end of said cinder chamber to the lower end of said combustion chamber to discharge said solids into the lower portion of the blast, and an air injection line opening into the inlet end 115 of said passage. 120
